Primary Examiner — Angela J Lee

(74) Attorney, Agent, or Firm — Michael Best and Friedrich LLP

(57) **CLAIM**

The ornamental design for a display panel or screen with a graphical user interface, as shown and described.

DESCRIPTION

FIGURE is a front elevational view of a display panel or screen with graphical user interface showing our new design.

The broken line showing of a display panel or screen, and other elements forms no part of the claimed design.

1 Claim, 1 Drawing Sheet(56)
